UNITED STATES PATENT OFFICE.

ROBERT STEWART, OF PITTSFIELD, ILLINOIS.

STEAM-BOILER CLEANER.

SPECIFICATION forming part of Letters Patent No. 295,070, dated March 11, 1884.

Application filed September 4, 1883. (No model.)

To all whom it may concern:

Be it known that I, ROBERT STEWART, a citizen of the United States, residing at Pittsfield, in the county of Pike, State of Illinois, 5 have invented a certain new and useful Steam-Boiler Cleaner, of which the following is a specification.

My invention relates to and is a device by which a steam-boiler may be cleaned of all sediment, and by which all scales formed by such sediment on the interior of such boiler are caused to become detached from said boiler, and to become pulverized and be thrown out of such boiler. To accomplish these results, I cause a 15 pipe to be placed at the bottom of a steam-boiler, inside the same, in the water, and near the lowest point. This pipe is to run lengthwise with the boiler. The rear end of this pipe is closed with a cap. At frequent intervals along said 20 pipe are inserted nipples or tubes from an inch to two inches long and screwed into said pipe. The outer ends of such nipples or tubes are beveled on the inside to an edge. Outside said boiler, upon said pipe, is attached an escape-valve of such a character as will permit 25 said pipe to be instantly opened to its full capacity and at once closed again. When all is thus arranged, by opening and closing this 30 valve quickly the rush of the water in said boiler, with the steam-pressure thereof, through said nipples or tubes, and then stopping this rush, will shock or vibrate the contents of the boiler, which, with the agitation of the water under steam-pressure, will cause all scales or 35 sediment to break off of the boiler, to be carried against the beveled nipples and broken up or pulverized, and then to be drawn off through said nipples or tubes into said pipe, and so out of said boiler. The said pipe and 40 said nipples or tubes must be of such size with relation to each other that the area of a cross-section of said pipe will be greater than the sum of the areas of the cross-sections of all the tubes or nipples.

Figure 1 represents a side view of a boiler 45 in place, with the pipe C C running into and along the bottom of the same. B represents the escape-valve.

Fig. 2 represents a view of the bottom of a boiler with pipe as located therein. C C is 50 the pipe; B, the escape-valve. a a a a are the nipples or tubes screwed into the pipe C C.

Fig. 3 represents one of the nipples or tubes. C is the pipe; A, the nipple or tube screwed into the pipe. The dotted lines d show how 55 the inside of the nipple or tube is beveled to an edge at d'.

Figs. 4 and 5 are end views of a boiler partly 60 broken away, showing application of invention.

I am aware that prior to my invention a 65 perforated pipe—such as or similar to pipe C—has been made and used to clean a boiler, in combination with an ordinary globe-valve. I am also aware that prior to my invention 70 valves of different patterns have been made that may be used to open a pipe instantly to its full capacity. I do not therefore claim such pipe, broadly, or such valve; but

What I do claim as my invention, and desire to secure by Letters Patent, is—

1. The combination, with a steam-boiler, of a pipe, C, situated near the bottom thereof, and provided with short tubes a, having sharp beveled ends d', and a valve, B, all of the above 75 parts combined and adapted to operate as described.

2. The combination, with a steam-boiler, of a pipe, C, situated near the bottom thereof, and provided with a series of short tubes, a, having sharp beveled ends d', the said pipe C being greater in cross-section than the sum of the areas of the cross-sections of the short tubes, substantially as set forth.

ROBERT STEWART.
